UNITED STATES PATENT OFFICE.

JOHN J. WALSH, OF YONKERS, NEW YORK.

MUSIC-LEAF TURNER.

SPECIFICATION forming part of Letters Patent No. 565,308, dated August 4, 1896.

Application filed July 9, 1895. Serial No. 555,422. (No model.)

To all whom it may concern:

Be it known that I, JOHN J. WALSH, of Yonkers, in the county of Westchester and State of New York, have invented a new and Improved Music-Leaf Turner, of which the following is a full, clear, and exact description.

My invention has for its object to provide a music-leaf turner capable of being attached to a piano, organ, or to a music-stand of any description without screwing or otherwise fastening the device to the support provided for it, thereby preventing the marring of the casing of the instrument or chafing a stand.

Another object of the invention is to construct a music-leaf turner in an exceedingly simple and durable manner, and to provide devices for attaching leaves of music to the several arms of the machine in a manner which will not act detrimentally to the sheets.

Another object of the invention is to provide for a quick releasing of the arms when a sheet of music is required to be turned, and furthermore providing a construction whereby all of the music-carrying arms of the machine may be simultaneously carried over to a position to receive the leaves, and locked in such position.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of a piano having the leaf-turner applied thereto. Fig. 2 is a vertical section through the leaf-turner, taken at a point near the center. Fig. 3 is a partial rear view of the leaf-turner, parts being broken away; and Fig. 4 is a detail perspective view of the leaf-receiving end of one of the leaf-carrying arms.

In carrying out the invention a casing A is provided as the body of the machine, and this casing is of box-like construction and need not necessarily be very large. The casing is preferably open at the back in the interest of lightness, and at the upper back portion of the body or casing of the machine at each side a rearwardly-extending bracket 10 is formed, and these brackets are adapted

to fit upon the ledge of the ordinary music-rack of a piano or organ or rest upon the leaf-supporting edge of the music-stand. 55 When the machine is applied to a piano, as shown in Fig. 1, the body or casing will extend down from the usual rack to a point near the keyboard.

The body or casing has a ledge 11 secured 60 upon its upper front edge, upon which the music is to rest, and this ledge extends any desired distance beyond each side of the casing. A music-rest 12 of any desired description and corresponding to the music-rack of 65 the instrument is hinged upon the back portion of the body and is supported, preferably, in a rearwardly-inclined position by means of arms 13, pivoted to the rear extensions of the casing and bearing against a batten 70 formed upon the rear of the said rest. These supporting-arms 13 may be independent of each other or they may be connected at the top.

The book or cover for the music is held in 75 engagement with the front of the rest-board of the machine and the said rest-board pressed against the arms 13 through the medium of clamping-arms 14 of spring character, which emanate, preferably, from the forward edge of 80 the ledge 11 and have bearing at their upper ends against the front face of the said rest-board, one near each side, as shown in Fig. 1, while a center pin or bar 15 is secured to the ledge 11 at its lower end and projects upwardly toward the upper edge of the rest-board 12. This pin or bar 15 serves to hold the sheets of music in place. This pin 15 is adapted to be placed vertically along the central portion of sheet-music or a book of music, 85 being between the leaves at opposite sides, and if in practice it is found desirable this pin may be of spring material and rigidly secured to the ledge 11 at its lower end, being free at its upper end. 95

Brackets 16 and 17 are formed upon the front of the casing, preferably at or near the center, and in these brackets the ends of a shaft 18 are firmly fastened. This shaft is adapted as bearings for music-carrying arms 100 C. Any desired number of these arms may be employed, and the arms are arranged one below the other and are graduated in length, the lower one being the longest and the upper

one the shortest. The arms comprise practically a substantially horizontal member *c* and a vertical member *c'*, the vertical members of all of the arms being parallel, as is shown in 5 Fig. 3.

Each music-carrying arm at the inner end of its horizontal member *c* is provided with a sleeve 19, through which the shaft 18 is passed, and springs 20 are coiled around the 10 shaft between the arms and the arms of the brackets in which the shaft is secured, the springs being secured at one end to the shaft and attached at their opposite ends to the horizontal members of the arms. The tendency of these springs is to carry the arms over 15 to the left-hand side of the machine, but the arms should be placed at the right-hand side of the machine when the sheets of music are attached to them and before the machine is 20 operated.

The vertical member *c'* of each music-carrying arm *C* is provided with a device for securing the sheet or leaf music to the arm, and this device preferably consists of a wire which 25 is bent or coiled upon itself, as shown at 21 in Fig. 4, the sheet or leaf to be attached to the arm being passed between adjacent members of the coil, and if in practice it is found desirable the music-carrying arms may be 30 made of stout wire and the coil or music-receiving device 21 be formed of the same material.

Each music-receiving device or coil is provided, preferably, with a disk 22 upon its front 35 face, adapted to have a number produced thereon, and the numbers on the various arms read from the innermost or shorter arm outward, as, for example, "1," "2," and "3," the numbers being intended to indicate the leaves 40 that have been turned, as, for example, when two of the arms have been shifted over the figure "3," appearing on the third arm still 45 in position, will indicate that two leaves have been turned.

45 The music-carrying arms are held at the right-hand side of the machine by means of latches 23, which are made to extend through an opening 24 in the front of the casing, and are pivoted at their rear ends on a rib 25, located at the rear of the casing and held by a cross-bar, as shown best in Fig. 2, and each latch terminates at its free end in a head adapted to receive and hold the music-carrying arms, the number of latches corresponding 55 to the number of arms. Each latch has a link 27 attached thereto, and these links are carried downward to the bottom portion of the casing, where each link is pivotally attached to a key-lever 28, fulcrumed in the 60 lower portion of the casing and extending out through the front board, slots 30 being provided for the purpose, and each key-lever at its outer end is provided with a disk 29, or

the equivalent thereof, to be struck by the finger when the sheet of music is to be turned. 65 These disks bear numbers corresponding to the numbers on the music-carrying arms that the latches they are connected with control, so that when the first leaf is to be turned the key marked "1" is pressed. If the third leaf 70 is to be turned, the key marked "3" will be pressed and the third arm will swing, carrying with it the appropriate leaf. When a key-lever is pressed, the latch 23 with which it is connected is raised and the arm that it 75 engaged will be released, and the spring controlling that arm will carry it over to the left-hand side of the machine.

Having thus described my invention, I claim as new and desire to secure by Letters 80 Patent—

1. In a music-leaf turner, the combination with a casing provided with a bracket projecting from its rear face for supporting it, and leaf-carrying arms carried by the casing, of a 85 music-rest hinged to the casing, and arms secured to the bracket of the casing and engaging the rest to support it in an inclined position, substantially as described.

2. In a music-leaf turner, the combination with a casing provided with a ledge on its upper front face and with a bracket projecting from its rear face for supporting it, and leaf-carrying arms carried by the casing, of a music-rest hinged to the casing, and arms 95 pivoted to the bracket of the casing and engaging the rest to hold it in an inclined position, substantially as described.

3. In a music-leaf turner, the combination with a casing having an open rear portion and 100 having its side walls extended rearwardly to form brackets capable of supporting the casing, of a cross-bar extended across the open rear portion of the casing and having a rib thereon, a series of catches pivotally mounted 105 on the rib and projected forwardly through an opening in the front of the casing, a series of leaf-turning arms pivoted on the casing and respectively engaged by the catches, means for swinging the leaf-turning arms, a 110 link pivotally connected to each catch, and keys mounted in the casing and respectively pivoted to the links, substantially as described.

4. In a music-leaf turner, the combination 115 with a casing, of operated leaf-turning arms, a music-rest hinged on the casing, an arm rising from the casing and supporting the music-rest, and a spring engaging the music-rest and pressing the same against the arm, 120 substantially as described.
